Specification for Design.

Patented Nov. 15, 1910.

Application filed October 6, 1910. Serial No. 585,729. Term of patent 14 years.

To all whom it may concern:

Be it known that I, THEODORE C. STEIMER, a citizen of the United States, residing at Pittsburg, in the county of Allegheny and State of Pennsylvania, have invented a new, original, and ornamental Design for Glass Dishes, of which the following is a specification, reference being had to the accompanying drawing, forming part thereof.

The drawing shows in elevation a glass dish embodying my design.

I claim:

The ornamental design for glass dish as shown.

In testimony whereof, I have hereunto set my hand.

THEODORE C. STEIMER.
